UNITED STATES PATENT OFFICE.

ARTHUR C. BECKWITH, OF EAST ST. LOUIS, ILLINOIS, ASSIGNOR, BY MESNE ASSIGNMENTS, TO THE WESTERN RAILWAY EQUIPMENT COMPANY, OF MISSOURI.

PNEUMATIC HAMMER.

SPECIFICATION forming part of Letters Patent No. 661,786, dated November 13, 1900.

Application filed September 1, 1899. Serial No. 729,226. (No model.)

To all whom it may concern:

Be it known that I, ARTHUR C. BECKWITH, a citizen of the United States, residing at the city of East St. Louis, county of St. Clair, State 5 of Illinois, have invented a certain new and useful Improvement in Pneumatic Hammers, of which the following is a full, clear, and exact description, such as will enable others skilled in the art to which it appertains to make and 10 use the same, reference being had to the accompanying drawings, forming part of this specification, in which—

Figure 1 is a longitudinal sectional view through my improved pneumatic hammer. Fig. 2 is a similar view showing the parts in 15 a different position. Fig. 3 is an enlarged elevational view. Fig. 4 is a cross-sectional view on line 4 4, Fig. 1. Fig. 5 is a cross-sectional view on line 5 5, Fig. 2. Fig. 6 is a top 20 plan view of the cylinder or barrel, showing the piston in dotted lines in its forward position. Fig. 7 is a bottom plan view of the cylinder or barrel, showing the piston in dotted 25 lines in its rearmost position. Fig. 8 is a top plan view of the piston. Fig. 9 is a bottom plan view of the piston; and Fig. 10 is a small 30 view of the cylinder, showing the piston therein in dotted lines, illustrating the manner in which the chamber in front of the piston is exhausted in the forward movement of said piston.

This invention relates to a new and useful improvement in pneumatic hammers, sometimes called "direct-acting engines," and is 35 designed to be used in connection with a chisel or like tool which is loosely mounted in an opening in the forward end or nose of the cylinder or barrel, the engine being held in the hand of an operator and guided in its work. 40 Motive fluid, preferably in the form of compressed air, is conducted to the engine through a flexible hose or tube leading from some suitable source of supply.

One object of this present invention is to 45 construct a tool of the character described with as few parts as possible consistent with the results obtained.

Another object is to make a tool of this description non-vibratory—that is, the shock or 50 jar of the piston striking on the inner end of

the chisel-shank will not be communicated to the operator.

Another object is to render a tool of this character automatic with respect to the cut-off of the motive fluid, so that when the engine is not in proper working position it will not idly reciprocate. 55

Another object incident to the automatic cut-off feature is the control or regulation with respect to the admission of the motive 60 fluid to the engine, making the same commensurate with the amount of pressure exerted by the operator in applying the tool to its work—that is, a light application of the engine in its work will result in the automatic 65 regulation with respect to the admission of motive fluid, so that the piston will deliver light blows, while a heavy pressure in applying the engine to its work will result in rendering the entire inlet-port area available for 70 the admission of the greatest amount of motive fluid, so that the piston will strike its hardest blows under such conditions.

With these objects in view the invention consists in the construction, arrangement, and 75 combination of the several parts, all as will hereinafter be described and afterward pointed out in the claims.

In the drawings, A indicates an open-ended sleeve carrying a suitable handle A' and provided with a threaded nipple-opening a for the attachment of a flexible supply-hose for the motive fluid. (Not shown.) The forward or open end of this sleeve may be provided with a series of exhaust-openings a'. 80

a² indicates an opening in the sleeve, to the rear of which and within the sleeve is arranged an inverted-T-shaped groove a³, whose purpose will hereinafter be described. 85

a⁴ indicates an opening leading from the closed end of the sleeve to the exterior to accommodate the escape and admission of air at atmospheric pressure behind the cylinder or barrel to prevent the same sticking or binding by reason of the cushioning effect of the confined air at this point. 90

B indicates a cylinder or barrel whose forward end or nose is formed with a suitable opening for the reception of a tool-shank C, which tool-shank is designed to entirely fill 100

- the opening and by so doing form a portion of the front wall of the cylinder. The rear end of the bore of this cylinder or barrel is formed with a shoulder, against which is seated a cylinder-head or cap-plate D, preferably formed with an inwardly-opening chamber about its center, while the flange affords a seat for a spring E, interposed between said cap-piece and the rear wall of the sleeve A.
- 10 F indicates a screw-bolt whose head is provided with a transverse rib f, forming a key or feather coöperating with the T-shaped groove a^3 in sleeve A. This bolt F is introduced through the opening a^2 in the sleeve 15 and threaded into a suitable opening in the cylinder or barrel B and carries on its inner end a tapered projection or stud f', which fits into a suitable recess or opening in a cam-roller G, which coöperates with the piston.
- 20 The head of bolt F prevents rotation of the cylinder in the sleeve and also arrests the forward longitudinal movement of said cylinder relative to said sleeve by abutting against the front wall of opening a^2 . Bolt F therefore 25 may be termed the "locking-key" between the cylinder and sleeve to prevent rotary motion of the cylinder within the sleeve and an excessive longitudinal motion of the cylinder relative to the sleeve, in addition to
- 30 which said bolt also affords a bearing for the piston cam-roller. Cylinder B is provided with an inlet-port b, communicating with the opening a through a suitable groove. (See Figs. 1, 2, and 7.) On each side of this inlet-35 port b are two exhaust-ports b' and b^2 , which open into a reduced portion b^3 , communicating with the atmosphere through the exhaust-ports a' or the opening a^2 in the sleeve.
- 40 b^4 is an exhaust-port leading from the cylinder and opening into the space b^3 .
- H is the piston, which is preferably made solid and of uniform diameter throughout its length, said piston operating in the bore of the cylinder, which bore is also of uniform diameter throughout its length. Piston H is provided with what I will term a "duplex" cam-groove, which is open at the forward end of said piston, but closed at its rear end. It will be seen by reference to Fig. 8 that the open 45 and closed ends of this cam-groove are of a width substantially equal to the diameter of the cam-roller G and that said ends are circumferentially displaced relative to each other to the extent approximately of about 50 forty-five degrees. For a short distance these ends of this cam-groove are formed with parallel side walls disposed longitudinally the axis of the piston, between which points these walls are outwardly curved with relation to 55 each other for the purpose of giving the piston a gradual and gentle turn while moving in either direction, the roller G at each limit of movement of the piston in either direction coöperating with the parallel walls of the ends 60 of the groove to hold the piston approximately in a fixed relation to the cylinder during the completion of its movement in one direction

and for a short period of time occupied by the piston at the commencement of its return movement. While the piston is free to play 70 when the roller is in a position between the curved walls of this groove, yet in actual operation the piston only turns an amount corresponding to the fluctuation of the cam-face with which it engages, the friction of the moving parts resisting independent movement of the piston. It will, however, be noted in this connection that intermediate the parallel end walls of this cam-groove the piston in one movement—say forward—is rotated or displaced circumferentially an amount equal to the distance between the port b and either of the ports b' or b^2 , a reverse circumferential movement occurring on the rearward stroke of the piston. This statement is of course 80 only true when the roller occupies a position intermediate the ends of the groove, a greater circumferential movement occurring as the piston moves either forward or backward beyond a point where this roller occupies the 85 central position above referred to. In the drawings I have marked the open front end of this cam-groove h , the rear closed end, which is circumferentially displaced about forty-five degrees, as h' , the outwardly-curved wall 90 or cam-face, which coöperates with the roller G when the piston is moving forward, as h^2 , and the oppositely-curved wall on the other side of the cam-groove, which coöperates with the roller G to rotate the piston in an opposite direction when said piston is moving rearwardly, as h^3 . This cam-groove, as above described, is preferably arranged on the upper half of the piston, as shown in the drawings, while on the opposite side or lower half of the 100 piston are arranged inlet and exhaust ports which open at opposite ends of the piston, respectively, said ports coöperating with the inlet and exhaust ports b, b' , and b^2 of the cylinder. The first of these piston-ports I 110 will describe consists of a groove substantially longitudinally disposed relative to the axis of said piston, as at h^4 , said groove being open at the rear end of the piston, while the forward end of said groove, as at h^5 , is arranged 115 at an angle, as shown in Fig. 9.

h^6 indicates a port in advance of but communicating with the groove h^5 , said port being preferably formed by drilling suitable openings in the piston.

h^7 indicates a port leading from a point to one side of the groove h^4 , near the rear end of the piston, and extending forwardly and opening through the front end of the piston, as shown in Fig. 9.

h^8 indicates a recess or port-opening communicating with the port h^7 , said port h^8 being located some distance in advance of the port-opening h^7 .

The operation of the engine is as follows: 130 The supply-pipe is connected to the threaded opening a and motive fluid admitted to the engine. In a non-operative position spring E forces the barrel or cylinder forward, so as

to close communication between the inlet-openings *a* and *b*, so that while said cylinder is in such forward position no motive fluid can be admitted to the engine. As stated before, this forward longitudinal movement of the cylinder is arrested by the bolt *F*, which prevents separation of the parts. When the chisel *C* is introduced into the nose of the cylinder, the operator grasps the handle *A'* with one hand while he guides the chisel in its work with the other. By pressing on the handle *A'* the spring *E* is compressed and the sleeve moves forward over the cylinder until the rear end of port *b* registers with the inlet-opening *a*. This opening can be controlled by the degree of pressure exerted on the handle *A'*, a slight pressure resulting in a small inlet-port opening, so that the piston will deliver light blows, while a heavier pressure insures a full inlet-port opening, admitting the greatest volume of motive fluid to the engine, which causes the piston to deliver its heaviest blows. The motive fluid entering port *b*, the parts being in the position shown in Fig. 1, will pass through the port *h⁷* to the chamber in front of the piston, giving the piston its first impulse or initial rearward movement. As the port *h⁷* passes out of registration with the inlet-port *b* the admission of motive fluid in front of the piston is cut off and the piston travels rearwardly by the expansion thereof until the port *h⁸* registers with the inlet-port *b*, when the piston receives its second impulse, the motive fluid being admitted to the front end of the piston through port *h⁸* for a short period of time, after which, or when port *h⁸* passes out of registration with the inlet-port *b*, the piston is forced rearwardly by the expansion of the motive fluid in front thereof. The air behind the piston is exhausted through the groove *h⁴ h⁵*, which registers with the exhaust-port *b'*. (See Fig. 4.) In the rearward movement of the piston the cam-roller *G* cooperates with the curved wall *h³* of the piston-groove, which causes the registration of the channel *h⁴ h⁵* with the exhaust-port *b'* for the greater movement of the piston; but just before the piston reaches its rearmost position the cam-roller rotates the piston sufficiently to carry the channel *h⁴* h⁵ out of registration with the exhaust-port *b'* and registers the port *h⁶* with the inlet-port *b*, so that a sufficient quantity of motive fluid is admitted behind the piston to act as a cushion and prevent the piston from striking the head *D*. Before the piston reaches the limit of its rearward movement the front end thereof passes the exhaust-opening *b'*, which, as shown in Fig. 6, is comparatively large to afford a quick exhaust, and as the major portion of the rearward movement of the piston is effected under expansion of the two impulses heretofore described it follows that after passing the front wall of the exhaust-opening *b'* the inertia only has to be overcome, which is accomplished by shutting off the exhaust to

form a cushion behind the piston and by admitting pressure behind the piston through the port *h⁶*. (See Figs. 2 and 5.) The port *h⁶* besides admitting pressure to form the cushion described also gives an initial impulse to the piston in its forward movement, and when the port *h⁶* passes out of registration with the inlet-port *b* the piston travels 75 from the expansion of the motive fluid first admitted until the forward end of the channel *h⁵* gets into registration with the inlet-port *b*, at and after which time the piston then travels forwardly under uninterrupted pressure, the roller *G*, coöperating with the curved side wall *h²* of the cam-groove, rotating the piston so that the inclination of the channel *h⁵* registers with the inlet-port *b* until the piston approaches the extremity of its forward movement, when the cam-groove forces the channel *h⁴* out of registration with the inlet-port. Just before the piston delivers its impacting blow on the tool-shank the motive fluid is cut off from behind the piston, and 80 the space in front of the piston is in communication with the atmosphere by the cam-groove being in registration with the exhaust-port *b'*, (see Fig. 10,) so that said space in front of the piston is being uninterruptedly 85 exhausted until the piston approaches the forward limit of its movement, when the final rotation of the piston carries the cam-groove out of registration with the port *b'*. The piston now delivers its blow, compressing the 90 air in front thereof, its final forward movement registering the port *h⁷* with the port *b*, so that the rebound of the piston is utilized, in conjunction with the cushion formed and the admission of motive fluid through the 95 port *h⁷*, to start the piston in its rearward movement. This cycle of operations is 100 repeated, the piston at the commencement of each forward and backward movement receiving initial impulses which serve to cushion the same at the end of its stroke, after which in the forward movement it has an uninterrupted admission of pressure behind the same and an uninterrupted exhaust in front thereof until approaching the completion of said movement, when the motive fluid is cut off. In its rearward movement the piston, after receiving its initial impulse, receives 105 a second impulse of longer duration, but for a comparatively short length of time, the major portion of the rearward movement of the piston resulting from the expansion of the motive fluid in front thereof derived from this second impulse, while the exhaust from behind the piston is uninterrupted in this 110 movement until the movement is about completed, when said exhaust is cut off. It will also be noted that cushions are formed to 115 prevent the piston striking the cylinder or barrel at each limit of movement, which cushions are assisted by the initial starting impulses, which may be said to be effective before the piston starts on its return stroke at either limit of movement, the cushions first

mentioned merely serving to slow down the speed of the piston preparatory to the admission of these impulses. When the chisel is removed from its work, the spring E forces the cylinder forwardly and closes communication with the inlet-ducts *a* and *b*, so that the cessation of motion in the engine is automatic when in a non-operative position. Not only is this true, but the absence of the chisel from the nose of the cylinder will also prevent the engine operating, even though the cylinder is forced rearwardly. For instance, as shown in Fig. 1, if the chisel-shank were removed so as to open communication between the space in front of the piston and the atmosphere the motive fluid would pass through port *h* and blow through to the exterior without forcing the piston rearwardly.

I am aware that minor changes in the arrangement, construction, and combination of the several parts of my device can be made and substituted for those herein shown and described without in the least departing from the nature and principle of my invention.

Having thus described my invention, what I claim, and desire to secure by Letters Patent, is—

1. The combination with a sleeve formed with an admission-port, of a cylinder slidably mounted in said sleeve and formed with an inlet-port or passage-way adapted to register with the sleeve-port when the cylinder is in a rear position, means for exerting a pressure tending to hold the cylinder in a forward position, and a piston carried by said cylinder; substantially as described.

2. The combination with a sleeve, of a longitudinally-movable cylinder mounted therein, said cylinder being formed with an inlet-port adapted to register with an inlet-port in the sleeve, and a spring for exerting pressure for forcing said cylinder forward to close said inlet-ports; substantially as described.

3. In a pneumatic hammer, the combination with a sleeve, of a slidable cylinder arranged therein, a piston carried by said cylinder, and means for exerting constant pressure against said cylinder to hold the same in a forward position, in which forward position the supply of motive fluid is cut off from the cylinder; substantially as described.

4. In a pneumatic hammer, the combination with a sleeve, of a slidable cylinder arranged therein, means for limiting the forward and backward movement of said cylinder, an expansible spring interposed between the rear end of the cylinder and the sleeve for exerting a constant pressure to hold the cylinder in a forward position, and a handle on the sleeve designed to be grasped by the operator in order that the pressure may be increased against the cylinder by compressing said spring when the sleeve is slid forward over the cylinder; substantially as described.

5. In a pneumatic hammer, the combination with a sleeve, of a longitudinally-mov-

able cylinder mounted therein, a piston mounted in said cylinder, a chisel-shank for receiving impacting blows from said piston, and a spring interposed between the sleeve and the rear end of the cylinder for rendering the machine inoperative when in normal position; substantially as described.

6. In a pneumatic hammer, the combination with a sleeve or support, of a cylinder mounted therein and adapted to move longitudinally thereof, a piston arranged in said cylinder, a chisel-shank mounted in the forward end of said cylinder, and means exerting a constant pressure to hold said cylinder in a forward position to cut off the supply of motive fluid therefrom; substantially as described.

7. In a pneumatic hammer, the combination with a sleeve or other support, of a longitudinally-movable cylinder mounted therein, means for preventing said cylinder from rotating in the sleeve, and a spring exerting its energy to hold said cylinder in a forward position; substantially as described.

8. In a pneumatic hammer, the combination with a sleeve or other support, of a longitudinally-movable cylinder mounted therein, a piston in said cylinder, a spring for holding said cylinder in a forward position and a chisel-shank which is received by an opening in the front end of the cylinder, said chisel-shank forming a portion of the front end wall of the cylinder; substantially as described.

9. In a pneumatic hammer, the combination with a sleeve, of a longitudinally-movable cylinder mounted therein, a longitudinally-movable head for closing the rear end of the cylinder, and a yielding medium interposed between the sleeve and the cylinder-head for yieldingly holding the latter in position; substantially as described.

10. The combination with a sleeve, of a longitudinally-movable cylinder mounted therein, a piston mounted in said cylinder, a bolt mounted in said cylinder for limiting its longitudinal movement and preventing rotation thereof; substantially as described.

11. The combination with a sleeve, of a longitudinally-movable cylinder mounted therein, a bolt mounted in said cylinder for limiting its longitudinal movement and preventing rotation thereof relative to the sleeve, a piston mounted in the cylinder and provided with a spiral groove, and a roller mounted on the end of said bolt and fitting in said groove; substantially as described.

12. The combination with a sleeve provided with an opening *a*², and a recessed portion *a*³ adjacent to said opening, a longitudinally-movable cylinder mounted in said sleeve, and a bolt which is introduced into a suitable opening in said cylinder through the opening *a*², the head of said bolt being received by the recess *a*³, when the cylinder is moved longitudinally in the sleeve; substantially as described.

13. The combination with a cylinder, of a

bolt formed with a tapered stud on its inner end projecting within the cylinder, a roller loosely mounted on said tapered stud, and a piston formed with a spiral groove for coöperating with said roller, said piston being also formed with ports coöperating with cylinder-ports, whereby when said piston is at or about the extremity of either movement it receives an impulse of comparatively short duration; substantially as described.

14. The combination with a cylinder provided with an inlet-port, and a piston formed with a plurality of ports coöperating with the cylinder-port in such manner that, in its forward movement, the piston receives an initial impulse and then an uninterrupted supply of motive fluid therebehind, and, in its rearward movement, said piston receives an initial impulse of short duration and then a second impulse of longer duration in front thereof, to force the piston rearwardly; substantially as described.

15. In a pneumatic hammer, the combination with a cylinder provided with an inlet-port, and a piston provided with a plurality of ports coöperating with the cylinder inlet-port in such manner that said piston, in its rearward movement, receives pressure in front thereof, in the form of impulses, said cylinder and piston being provided with coöperating ports whereby, when the piston is moving rearwardly, the pressure therebehind is exhausted uninterruptedly; substantially as described.

16. A pneumatic hammer comprising a cylinder having a bearing for a tool at one end and provided with an inlet-port and exhaust-ports on each side of said inlet-port, and a piston fitted to slide and turn in the cylinder, said piston being provided with blind passages h^6 , h^7 , and h^8 , and an open passage h^4 , h^5 ; substantially as described.

17. A pneumatic hammer comprising a cylinder having a bearing for a tool at one end and provided with an inlet-port and exhaust-ports on each side of said inlet-port, a piston fitted to slide and turn in the cylinder, said piston being provided with blind passages h^6 , h^7 , and h^8 , and an open passage h^4 , h^5 , said piston being also provided with a spiral groove, and a roller carried by the cylinder and working in the said spiral groove; substantially as described.

18. A pneumatic hammer comprising a cylinder having a bearing for a tool at one end and provided with an inlet-port and exhaust-ports on each side of said inlet-port, a piston fitted to slide and turn in the cylinder, said piston being provided with blind passages h^6 , h^7 , and h^8 , and an open passage h^4 , h^5 , the piston being also provided with a spiral groove open at one end thereof, oppositely-curved walls of said groove intermediate the ends coöperating with a fixed roller to partially rotate said piston at different points in its forward and backward movements, and a stationary roller mounted in the cylinder for co-operating with said piston-groove; substantially as described.

19. In a pneumatic hammer, the combination with a sleeve or other support, of a cylinder longitudinally movable therein, a piston carried by said cylinder, a chisel forming a portion of the front end wall of the cylinder, and a spring-pressed movable cap piece or head forming the rear wall of said cylinder; substantially as described.

In testimony whereof I hereunto affix my signature, in the presence of two witnesses, this 29th day of August, 1899.

ARTHUR C. BECKWITH.
